UNITED STATES PATENT OFFICE.

JAMES E. SYKES, OF SNOHOMISH, WASHINGTON, ASSIGNOR OF ONE-THIRD TO A. HENNING, OF SNOHOMISH, WASHINGTON.

SMOKE-CONSUMER.

1,128,548.

Specification of Letters Patent. Patented Feb. 16, 1915.

Application filed March 6, 1914. Serial No. 823,000.

To all whom it may concern:

Be it known that I, JAMES E. SYKES, a citizen of the United States, residing at Snohomish, in the county of Snohomish and 5 State of Washington, have invented new and useful Improvements in Smoke-Consumers, of which the following is a specification.

This invention is an improved smoke consuming apparatus, the object of the invention being to provide an improved device of this character which is cheap and simple, which is easily operated, and which may be readily kept in order.

15 The invention consists in the construction, combination and arrangement of devices hereinafter described and claimed.

In the accompanying drawings:—Figure 1 is a vertical longitudinal sectional view of 20 my improved smoke consuming apparatus. Fig. 2 is a vertical transverse sectional view of the same on the plane indicated by the line *a—a* of Fig. 1. Fig. 3 is a detail sectional view of the same on the plane indicated by the line *b—b* of Fig. 1.

In accordance with my invention I provide a casing 1 which is here shown as of 25 oblong rectangular form and which in practice is preferably made of plate iron but 30 may be made of sheet iron or other suitable material. At the rear end of the casing is a manhole 2 and a disk 3 for closing the said manhole. The lower-portion of the casing forms a water compartment 4 which is 35 provided with an outlet 5 at the front end of the casing and which is spaced a suitable distance above the bottom of the said compartment so as to keep water at a desired level therein. Above the water compartment, 40 at a suitable height is a horizontally arranged screen 6 which is coextensive in width with the casing and extends from the rear wall thereof to within a short distance from the front wall 7 of the casing. A vertical 45 partition plate 8 is arranged in the casing at a slight distance from its front wall. The screen 6 extends to the said partition plate and the latter projects above and below said screen. An inclined washer 50 plate 9 is arranged in the casing with its lower end on the upper end of the partition plate 8 and its upper end secured to the top 10 of the casing and at a slight distance to the rear of the smoke intake opening 11. An 55 inclined screen 12 which is substantially at

right angles to the washer plate is arranged slightly above said washer plate and at a suitable distance in front of the smoke intake opening 11, this screen extending to the top of the casing and also extending from 60 side to side thereof. A washer plate 13 which is inclined and is arranged at substantially right angles to the washer plate 9 extends from the front wall of the casing downwardly and rearwardly to within 65 a slight distance of the washer plate 9. An inclined baffle plate 14 is arranged below the washer plate 9 and extends downwardly and rearwardly therefrom to a point a slight distance above the screen 6 and in front of 70 the rear wall of the casing. The rear wall of the casing has a discharge opening 15 a suitable distance from its upper end.

A water pipe 16 is provided with a sprayer arm 17 which extends across and is 75 arranged at the upper end of the washer plate 9. Similar pipes 18 are provided with sprayer arms 19 which are arranged near the upper side of the screen 12 on opposite sides thereof and extend across the same 80 and are provided with jet openings to discharge jets of water on opposite sides of said screen 12. A water pipe 20 is also provided which has a sprayer arm 21 that extends across the upper side of the inclined 85 washer plate 13 and is arranged to discharge jets of water on said washer plate.

In the operation of my invention the smoke which is admitted at *a* is forced through the screen 12 and under the washer 90 plate 13 and down through the duct 28 into the water compartment 4 and then upwardly through the screen 6 into the compartment 29 and under the baffle plate 14 into the compartment 30 and hence to the 95 discharge opening 15. As the smoke enters the smoke consumer it is acted upon by the spray of water from the arm 17 of the pipe 16 and washed, so that the solid particles are caused to drop on the washer plate 9 100 and to be carried downwardly thereon and the smoke is also washed by the spray from the arms 19 of the pipes 18 as it passes through the screen 12 so that a further separation of the solid particles from the smoke 105 body is effected by the screen and as the smoke strikes the washer plate 13 which forms a baffle, it is further washed by the spray from the arm 21 of the pipe 20, washer plate 13 and being discharged on the lower 110

portion of the washer plate and finally therefrom down through the duct 28 into the water in the water compartment 4. As the smoke passes up from the water compartment 5 it is caused to go through the screen 6 which arrests such particles as it may still carry, the smoke then striking the baffle plate 14 and being downwardly deflected thereby so as to cause such particles as may still be 10 carried by the smoke to drop on the screen 6 and as the smoke passes under the baffle plate 14 it rises in the compartment 30 and is discharged at 15.

Having thus described my invention, I 15 claim:—

The herein described smoke consumer having a smoke intake at its upper side and a discharge opening at one end, an inclined washer plate having its upper end connected 20 to the upper side of the casing at a point between the intake and discharge openings, and having its lower end spaced from the opposite end of the casing and provided with a downwardly extending vertical partition plate, the lower portion of the casing forming a precipitating chamber and said 25

partition plate extending down into said precipitating chamber, a screen forming the top of the said precipitating chamber and extending from said partition plate to the 30 end of the casing having the discharge opening, a screen extending downwardly from the top of the casing toward the inclined washer plate and arranged in rear of the intake opening, a second inclined washer plate arranged above the rear portion of the first named washer plate and connected at its upper side to the rear side of the casing, means to spray water on said washer plates and on the second named screen, and a 40 baffle plate extending downwardly from the first named washer plate, over the first named screen and inclining downwardly toward the end of the casing having the discharge opening. 45

In testimony whereof I affix my signature in presence of two witnesses.

JAMES E. SYKES.
